HAT BOX

Filed May 10, 1926

FIG. 2

BY
Robert N. Killgore
ATTORNEY

UNITED STATES PATENT OFFICE.

JESSE DREYFUS, OF NEW YORK, N. Y.

HAT BOX.

Application filed May 10, 1926. Serial No. 108,070.

My invention relates to improvements in hat boxes of the hand luggage type wherein a relatively deep compartment is provided for securely holding a woman's hat in transit and a tray is also provided for holding various articles. Pockets may be provided in the different compartments to hold articles. Heretofore such hat boxes have been made with a loose tray which was carried above the hat compartment and had to be removed before the hat could be taken out. I employ a tray which is an integral part of the hat box and so construct the latter that access may be had to either the tray or the hat compartment without any interference.

In the drawing Fig. 1 is a side view, partly in section of my improved hat box and Fig. 2 a top view, also partly in section, of the structure of Fig. 1.

The hat box comprises three main sections. The relatively deep hat compartment *a* has a bottom 1 and sides 2, being preferably flattened at the back 3 to enable it to stand up without rolling and to enable a pair of hinges to be used. A hat block 4 is secured inside the bottom 1 so that a hat may be pinned thereto and held against movement.

A tray *b*, having a permanently secured bottom 5 closing the top of the hat compartment and side walls 6, of the same contour as the body *a*, is hinged to the hat compartment at 7.

A cover *c*, with a top 8 and side walls 9, also the same contour as the body, is hinged to the tray walls and co-operates with the tray to form a shallow compartment for wearing apparel and accessories.

Pockets 10 and 11 may be secured to the under side of the cover and tray to hold articles if desired. The upper edge of the side wall of the hat compartment has an

inner flange 16 forming a shoulder for receiving the lower edge of the side walls of the tray which is positioned above the hat compartment and the side walls of the tray have a like flange 17 forming a shoulder at its upper edge. The cover has a short flange 18 fitting in the shoulder formed by the upper flange of the tray to make the case dust tight and stiff when closed.

A handle 12 is provided for carrying purposes and a lock 13 and catches 14 serve to hold the hat compartment *a* and tray *b* securely closed. Like locks 15 serve to hold the cover *c* to the tray *b* when the box is closed.

In use the lock 13 and catches 14 may be loosened and the tray and cover thrown back as a unit to obtain access to the hat compartment, or the locks 15 may be released to throw back the lid and obtain access to the tray. In this way a loose, removable tray is obviated and a unitary structure, without loose parts, is obtained.

I claim:—

A hat box comprising a relatively deep hat compartment, the upper edge of the side wall of said compartment having an inner flange forming a shoulder for receiving the lower edge of the side wall of a tray positioned above the hat compartment, the tray having a permanently secured bottom closing the top of the hat compartment, the side wall of the tray having an inner flange forming a shoulder at its upper edge, a cover having a short flange fitting in the shoulder formed by the upper flange of the tray, said cover co-operating with said tray to form a shallow compartment for wearing apparel and accessories, and separate, independent locking means for retaining the hat compartment and the tray in closed position.

JESSE DREYFUS.
